UNITED STATES PATENT OFFICE.

HARRY H. GUNKEL, OF CHICAGO, ILLINOIS.

DESIGN FOR AN INSEAM-MEASURING STICK.

60,139.

Specification for Design.

Patented Jan. 3, 1922.

Application filed June 24, 1921. Serial No. 480,241. Term of patent 14 years.

To all whom it may concern:

Be it known that I, HARRY H. GUNKEL, a citizen of the United States, residing at Chicago, in the county of Cook and State of Illinois, have invented a new, original, and ornamental Design for an Inseam-Measuring Stick, of which the following is a specification, reference being had to the accompanying drawing, forming part thereof.

Fig. 1 is a side elevation of an inseam measuring stick showing my new design.

Fig. 2 is an edge elevation of the same.

I claim:

The ornamental design for an inseam measuring stick, as shown.

HARRY H. GUNKEL.
